CLAIM

The ornamental design for a container lid as shown and described.

DESCRIPTION

FIG. 1 is a right, front, top perspective view of a container lid showing my new design;

FIG. 2 is a left, rear, bottom perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof;

FIG. 8 is a bottom plan view thereof;

FIG. 9 is a right, front, top perspective exploded view of the container lid in FIG. 1; and,

FIG. 10 is a right, front, top perspective view of the container lid in a using state.

In the drawings, the broken lines are shown for the purpose of illustrating both parts of the article as well as boundaries of the claim. None of the broken lines form part of the claimed design.

1 Claim, 10 Drawing Sheets
